No. 717,871.

PATENTED JAN. 6, 1903.

J. LEITSCHUH.
COMBINATION DRAFTING INSTRUMENT.

APPLICATION FILED JULY 5, 1902.

NO MODEL.

UNITED STATES PATENT OFFICE.

JOSEPH LEITSCHUH, OF DAYTON, OHIO.

COMBINATION DRAFTING INSTRUMENT.

SPECIFICATION forming part of Letters Patent No. 717,871, dated January 6, 1903.

Application filed July 5, 1902. Serial No. 114,830. (No model.)

To all whom it may concern:

Be it known that I, JOSEPH LEITSCHUH, a citizen of the United States, residing at Dayton, in the county of Montgomery and State of Ohio, have invented certain new and useful Improvements in Combination Drafting Instruments, of which the following is a specification, reference being had therein to the accompanying drawings.

10 This invention relates to combination drafting instruments, and has for its object to provide an instrument which combines in itself a straight-edge or rule, a compass, a divider, a protractor, a T-square, a bevel, and a beam-15 compass or trammel, the construction being such that the instrument is readily changed from one form to the other and is compact, readily portable, durable, and inexpensive of construction.

20 To these ends my invention consists in certain novel features, which I will now proceed to describe and will then particularly point out in the claims.

In the accompanying drawings, Figure 1 is an elevation of an instrument embodying my invention in one form. Fig. 2 is a similar view illustrating the use of the device as a compass, the position of the parts for use as a square being indicated by dotted lines. Fig. 3 is an enlarged detail sectional view taken on the line $x-x$ of Fig. 1. Fig. 4 is a view illustrating the use of the device as a trammel or beam-compass, and Fig. 5 is an enlarged detail view of one of the attachments employed in the construction shown in Fig. 4.

In the said drawings, 1 indicates the metal body of the instrument, which is triangular in cross-section, as shown in Fig. 3, the three faces being indicated, respectively, by the reference-numerals 2, 3, and 4. The body is provided at one end with a needle-point 5 and at the other end with a knurled head 6, and both head and point may be made removable by a screw-threaded connection with the body. The interior of the body is hollowed out for the greater portion of its length, as indicated at 7, and the interior space thus formed is closed by a plate 8, fitting in rabbed seats 9 at the edges of the opening 7 and lying flush with the face 4 of the body, of which face it forms a part when in place. The plate is removably secured in position

by means of screws 10, one at each end, and is provided with a longitudinal slot 11, extending substantially the entire length of the 55 plate. It will be observed that the plate 8 is let into the face 4 of the body, so as to be flush therewith.

In connection with the body 1 I employ an adjustable arm 12, consisting of a flat bar or 60 plate of a width equal or substantially equal to the face 4 of the body 1, against which it is adapted to lie flat. The arm 12 is provided with a longitudinal slot 13, and a screw 14 passes through the slot 13 and also through 65 the slot 11 of the plate 8, the outer end of the said screw being provided with a knurled head, while its inner end is threaded into a block 15, which fits and slides within the hollow interior space 7 of the body 1. The arm 70 12 is provided at one end with a needle-point 16 and at the other end with a pencil-point 17, both adjustable and removable in the usual manner.

One of the two free faces of the body 1 is 75 divided along its edge, as indicated at 18, into inches and subdivisions thereof or on any other suitable scale, so as to form a measuring-rule, as well as a straight-edge. The face 4 of the instrument is provided at one or both 80 ends with a protractor-scale 19, this scale being preferably formed on the end of the plate 8 which is rounded at its extremity and the lines of the scale diverging from the end of the slot in said plate. The face 4 is also provided with diagonal lines 20 at different angles to the axis of the body, so as to permit the ready laying off of angles on each side of said body at different points thereof. A line 23 drawn across the face 4 of the instrument 85 at right angles to the axis thereof enables the arm 12 to be brought into position for use as a square, as indicated in dotted lines in Fig. 2. It will be seen that the instrument as thus organized may be used as a compass, 90 as indicated in Fig. 2, the point of connection between the arm 12 and body 1 being varied as desired by moving the block 15 within the body 1 and moving the arm 12 relatively to the clamping-screw 14, as desired. 95 The arm 12 may be so turned as to use either the needle-point 16, thus making the instrument a divider, or the pencil-point 17, thus using the instrument as a compass. When

not in use, the arm 12 may be caused to lie flat against the face 4, with its edges parallel with the edges thereof, and when clamped in this position, which is shown in Fig. 1, the instrument may be readily carried in the pocket, being compact and well adapted for this purpose. By placing either edge of the arm 12 to register with the lines 23 or 20 the instrument may be used as a square or bevel, and 10 by similar use of the arm 12 in connection with the scales 19 the instrument may be used as a protractor. This latter operation may be accomplished by shifting the arm 12 longitudinally of the slot, so as to bring one of 15 its edges into proper relation with the lines of the protractor-scale 19, so as to cause it to indicate the desired angle.

When it is desired to use the instrument as a trammel or beam-compass, I provide the 20 attachments shown in Figs. 4 and 5, in which 24 indicates an arm provided with a needle-point 25 and having a divided loop 26, triangular in form and adapted to fit over the body 1, on which it may be clamped by a screw 27. 25 28 indicates a similar arm provided with a divided triangular loop 29, adapted to be clamped on the bar by a screw 30. This arm 28 has pivoted on it, by means of a combined pivot and clamping-screw 31, an extension 32, 30 carrying a point or pencil 33, said extension being provided on its upper edge with a worm-gear segment 34, with which meshes a worm 35, mounted in suitable brackets on the arm 28 and having a head 36, by means of which 35 it may be rotated, so as to provide for the adjustment of the extension 32, which latter may be clamped in position by means of the screw 31 after adjustment. These trammel-points may be readily slipped over the body 40 and secured thereon at the desired distance apart, and this distance may be further nicely regulated by means of the worm 34.

I do not wish to be understood as limiting myself to the precise details of construction 45 hereinbefore described, and shown in the accompanying drawings, as these details may obviously be modified without departing from the principle of my invention.

Having thus fully described my invention, 50 what I claim as new, and desire to secure by Letters Patent, is—

1. A combination drafting instrument comprising a body triangular in cross-section and having a longitudinal internal recess and a 55 face provided with a longitudinal slot communicating therewith, a block sliding in said

recess, a longitudinally-slotted arm provided at its opposite ends with a needle-point and pencil-point, respectively, and a clamping-screw passing through both slots and screwing into the block, said body portion being provided at one end with a needle-point, substantially as described. 60

2. A combination drafting instrument comprising a body triangular in cross-section and 65 having a longitudinal internal recess and a face provided with a longitudinal slot communicating therewith, a block sliding in said recess, a longitudinally-slotted arm provided at its opposite ends with a needle-point and pencil-point, respectively, and a clamping-screw passing through both slots and screwing into the block, said body portion being provided at one end with a needle-point, and 70 at the other end with a knurled head, substantially as described. 75

3. A combination drafting instrument comprising a body triangular in cross-section and having a longitudinal internal recess, a slotted plate closing said recess, and a block sliding within the recess and held in position by the plate, in combination with a longitudinally-slotted arm provided at its respective ends with a needle-point and a pencil-point, and a clamping-screw passing through both 85 slots and threaded into the block, said body being provided at one end with a needle-point and at the other end with a knurled head, substantially as described. 80

4. In a combination drafting instrument, 90 the combination, with a body triangular in cross-section, having one of its edges divided and having a longitudinal recess closed by a slotted removable plate, said plate having protractor-scales at its ends, and transverse 95 lines at right and other angles to the axis of the body, and said body being provided with a needle-point at one end and a knurled head at the other, of a longitudinally-slotted arm provided at its respective ends with a pencil-point and a needle-point, a block sliding in the interior recess of the body, and a clamping-screw passing through both slots and threaded into the block, substantially as described. 100

In testimony whereof I affix my signature in presence of two witnesses.

JOSEPH LEITSCHUH.
